WOODEN WINDOW SASH

Emil K. Geyser, Pittsburgh, Pa.

Application June 4, 1942, Serial No. 445,705

6 Claims. (Cl. 20—56)

This invention relates to window sash, and more particularly to wooden window sash of large size such as used in industrial buildings, schools, and the like.

In my Patent No. 2,201,577 a window sash is disclosed that is of the same general form and for the same general purpose as the sash to be disclosed herein. However, my patented sash is made of metal which the war has made very difficult to obtain for such purposes, and is constructed in a way that is not suitable for wooden sash. I have therefore invented a window sash of the same general character which is made of wood and which can be shipped in the knock-down and readily assembled in unlimited sizes at the building site as the case with my metal window.

It is among the objects of this invention to provide a window sash of wood which is adapted to be fabricated as it is being installed in the window opening of a building, which can be readily formed in any desired size, which can be quickly and easily assembled, which is strong and durable, which is relatively inexpensive to make and install, in which the glass can be quickly installed, and in which the metal members that fasten the vertical and horizontal members together are protected from the weather.

In accordance with this invention a window sash adapted to fill a window opening of any desired size is fabricated of wooden members in the opening itself as it is being installed therein. That is, a plurality of vertical mullions first are connected at their ends to the top and bottom members framing the window opening, a sufficient number of mullions being used to give the desired spaces between them for panes of glass throughout the width of the window. A plurality of vertically spaced horizontal members are then fastened to the front of the vertical mullions to form rectangular glass-receiving openings. To position the horizontal members the front portions of the mullions are provided with transverse notches that receive the horizontal members which are held in place in any suitable manner. It is preferred to slope the top and bottom walls of the notches downwardly from the front faces of the mullions and to likewise slope the top and bottom surfaces of the horizontal members downwardly toward their rear surfaces so that they will fit into the notches. Screws or other fastening members can then be inserted between the top walls of each horizontal member and notch with the screw threads embedded in the member and adjoining mullion for locking the horizontal

member in place. The upper and lower surfaces of the horizontal members preferably are provided with longitudinal channels for receiving the top and bottom edges of panes of glass the ends 5 of which overlap the vertical mullions and the screws that hold the horizontal members in place. Each mullion preferably is provided along the central portion of its front surface with an integral vertical rib projecting between the ends 10 of the panes of glass on both sides of it.

The preferred embodiment of the invention is illustrated in the accompanying drawing in which Fig. 1 is a fragmentary front view of my window sash installed in the wall of a building; 15 Fig. 2 is an enlarged vertical section taken on the broken line II—II of Fig. 1; and Fig. 3 is an enlarged horizontal section taken on the broken line III—III of Fig. 1.

Referring to the drawing, the wall 1 of a building is provided with a window opening of any desired size. Extending along the top of the opening is a horizontal framing member 2 that engages a vertical framing member 3 at each end. Extending along the bottom of the opening is a 20 sill 4 on which a horizontal framing member 5 rests. All of these members are made of wood and are joined together in any suitable manner.

It is a feature of this invention that the wooden sash that is installed in the window opening is 25 delivered to the building site in knock-down condition and is assembled or fabricated in the window opening itself, whereby the construction and installation of the sash are combined into one operation and their cost thereby reduced. The 30 first step is to individually and directly connect the ends of a plurality of separate vertical mullions 1 to the upper and lower framing members 2 and 5 in the window opening by any suitable means. These mullions are disposed at predetermined horizontally spaced intervals across the 35 entire width of the opening with the end framing members 3 serving as the end mullions of the window. A plurality of separate horizontal members or bars 8 are then individually connected to the front of the vertical mullions at vertically spaced intervals in a manner to be described presently. The number of bars used will depend, of course, upon the desired height of the glass-receiving openings and the height of the window. 40 The bars extend the full width of the window, being disposed end to end with their joints overlapping the mullions when the window is too wide for a bar of convenient length.

The horizontal bars are formed to facilitate 45 simple and rapid installation of the panes of glass

9 without the use of separate fastening members. For this purpose each of the bars preferably is provided with upper and lower channels 11 and 12 (Fig. 2) the lower one of which is deeper than the upper one so that the upper edge of a pane of glass can be inserted in the lower channel of a bar, raised therein until its lower edge clears the top of the bar below it, and then lowered into the shallow upper channel of the lower bar with the upper edge of the glass still retained in the deeper bottom channel of the upper bar.

To position the horizontal bars 8 and hold them parallel, the vertical mullions, including the end framing members 3, are provided in their front portions with vertically spaced transverse notches 14 in which the bars are mounted, as shown in Fig. 2. The notches are of such depth that the rear walls of glass-receiving channels 11 and 12 are located substantially flush with the front surfaces of the mullions so that the ends of the glass panes overlap the mullions in close proximity thereto. To line up the panes of glass and to improve the appearance of the window each of the vertical mullions is provided along the center of its front surface with a vertical rib 15 integral therewith. This rib projects between the ends of the adjacent panes of glass, but not an appreciable distance beyond their outer surfaces.

The horizontal bars are securely retained in the mullions in a simple but effective manner by sloping the top and bottom walls of notches 14 downwardly from the front of the mullions and by similarly sloping the top and bottom surfaces of bars 8 downwardly from their channels 11 and 12 toward their rear sides. Fastening members inserted between the top walls of the bars and notches prevent the bars from tipping out of the notches, while the bottoms of the bars are locked in the notches by the inclination of their bottom walls. Preferably, screws 16 (Fig. 2) are used as the fastening members with their threads embedded in the adjoining upper surfaces of the bars and notches. The heads of the screws are forced into the wooden mullions far enough to prevent them from interfering with setting of the glass in the channels, and are thus protected from the weather by the glass so that steel screws can be used rather than brass which is now difficult to obtain for such purposes.

The upper portion of the window shown in the drawing is provided with a hinged section for ventilating purposes, and the lower portion of the window may be provided with a similar ventilator if desired. The hinged section comprises a wooden frame 21 hinged at its top to the bottom of the upper horizontal member of the window so that the bottom of the frame can be swung out. This frame is divided into glass-receiving sections by short vertical members 22 in front of mullions 7 and the upper portions of which are cut away to receive these members. Each of these vertical members has an integral rib 23 along the center of its front projecting between the ends of the adjoining panes of glass. As shown in Fig. 3, these ribs project farther than those on the mullions in order to strengthen the hinged frame. Directly behind each end of the hinged ventilator is a small rectangular frame 24 mounted in fixed position and provided with a pane of glass 25 for intercepting rain that may blow in past the end of the open ventilator.

The ends of the window are finished by mounting a vertical facing strip 27 against the front of each of the end members 3. The rear side of

each facing strip is notched to receive and enclose the portions of horizontal bars 8 projecting from the vertical end members.

With a window sash constructed in accordance with this invention the window frame and the sash frame are combined into one with the resulting economies. There is no factory fabrication of the sash, and it is cheaper to handle before installation because it can be shipped and handled in knock-down condition. The method of assembly is simple and rapid. Windows of any desired size can be furnished with a single sash, whereby the cost of making several sash and connecting them together in a single window opening is avoided.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A window sash of wood, comprising a plurality of laterally spaced vertical mullions, a plurality of vertically spaced horizontal members provided in their upper and lower surfaces with longitudinal channels for receiving the top and bottom edges of panes of glass, said mullions being provided in their front portions with transverse notches for receiving said members with the rear walls of said channels substantially flush with the front surfaces of the mullions, and means for fastening said horizontal members to the mullions.

2. A window sash of wood, comprising a plurality of laterally spaced vertical mullions each provided along the central portion of its front surface with a vertical rib, a plurality of vertically spaced horizontal members provided in their upper and lower surfaces with longitudinal channels for receiving the top and bottom edges of panes of glass, said mullions being provided in their front portions with transverse notches for receiving said members with the rear walls of said channels substantially flush with said front surfaces whereby the ends of the glass panes can be disposed adjacent the sides of said ribs, and means for fastening said horizontal members to the mullions.

3. A window sash of wood, comprising a plurality of laterally spaced vertical mullions, a plurality of vertically spaced horizontal members provided in their upper and lower surfaces with longitudinal channels for receiving the top and bottom edges of panes of glass, said mullions being provided in their front portions with transverse notches for receiving said members with the rear walls of said channels substantially flush with the front surfaces of the mullions, the top and bottom walls of said notches sloping downwardly from said front surfaces and the top and bottom surfaces of said members behind the channels also sloping downwardly toward their rear surfaces to fit said notches, and means for fastening said horizontal members to the mullions.

4. A window sash of wood, comprising a plurality of laterally spaced vertical mullions, a plurality of vertically spaced horizontal members provided in their upper and lower surfaces with longitudinal channels for receiving the top and bottom edges of panes of glass, said mullions being provided in their front portions with trans-

verse notches for receiving said members with the rear walls of said channels substantially flush with the front surfaces of the mullions, the top and bottom walls of said notches sloping downwardly from said front surfaces and the top and bottom surfaces of said members behind the channels also sloping downwardly away from the channels to fit said notches, and fastening members inserted between the top walls of each horizontal member and notch for holding said members in place.

5. A window sash of wood, comprising a plurality of laterally spaced vertical mullions, a plurality of vertically spaced horizontal members provided in their upper and lower surfaces with longitudinal channels for receiving the top and bottom edges of panes of glass, said mullions being provided in their front portions with transverse notches for receiving said members with the rear walls of said channels substantially flush with the front surfaces of the mullions, the top and bottom walls of said notches sloping downwardly from said front surfaces and the top and bottom surfaces of said members behind the channels also sloping downwardly away from the channels to fit said notches, and screws inserted between the top walls of each horizontal member and notch with the screw threads embedded in

10 member and adjoining mullion for holding the horizontal members in place.

6. A window sash assembled in a substantially complete window opening having top and bottom framing members, said sash comprising a plurality of laterally spaced vertical mullions fastened at their ends to said framing members, each of said mullions being provided along the central portion of its front surface with a vertical rib, a plurality of vertically spaced horizontal members provided in their upper and lower surfaces with channels for receiving the top and bottom edges of panes of glass, said mullions being provided in their front portions with transverse notches for receiving said horizontal members with the rear walls of their channels substantially flush with said front surfaces, the top and bottom walls of said notches sloping downwardly from said front surfaces and the top and bottom walls of said horizontal members behind the channels also sloping downwardly away from the channels to fit said notches, and screws inserted between the top walls of each horizontal member and notch with the screw threads embedded in

20 25 said member and adjoining mullion for holding the horizontal members in place.
